UNITED STATES PATENT OFFICE.

JOHN F. GAIL, OF EVANSTON, ILLINOIS, ASSIGNOR TO SIMMONS COMPANY, OF NEW YORK, N. Y., A CORPORATION OF DELAWARE.

SPRING-INSERTING MECHANISM.

Application filed August 22, 1925. Serial No. 51,729.

My invention relates to improvements in machines for inserting springs into open ended flexible pockets and, although possibly susceptible of different applications, is particularly adapted for the purpose of manufacturing cushions or mattresses of the type disclosed in the United States patent to Marshall, No. 685,160.

Heretofore, the springs or helicals of the 10 Marshall construction have been generally inserted into the pockets or strips of pockets by hand or by manually actuated devices such as disclosed in the United States patents to Shields, No. 1,445,416, Genge No. 1,370,533 or 15 Read, No. 1,218,314. In these forms of apparatus the spring has been thrust into the pocket by some form of pusher mechanism which placed the spring directly in the pocket in the position to be occupied by said spring 20 permanently, i. e. with its axis aligned with the axis of the pocket.

The patent to Meutsch et al., No. 1,348,654 describes a machine for compressing the 25 springs longitudinally and then thrusting the same radially or laterally into the pockets so that the axes of the springs extend transversely across the pocket instead of in their true final position longitudinally thereof. However, these patentees do not disclose any 30 means or apparatus for turning the springs into their correct longitudinal position after the open ends of the pockets have been closed or sewed. Although such spring turning 35 may be effected manually, the construction of a satisfactory apparatus for performing this step automatically involves considerable difficulty.

The principal objects of the invention are to provide means for placing springs in such 40 pockets substantially automatically; to perform such inserting operation in such manner that the springs are placed in the pockets in their true or final position; to provide improved means for actuating the retaining 45 clamps by which the springs are prevented from retracting during the subsequent operation of closing the ends of the pockets; to provide means whereby springs received from or deposited by a coiling mechanism are 50 transported and inserted into the pockets; to provide an improved arrangement whereby the making or feeding of the springs may proceed uninterruptedly while the filled strips are being removed and the unfilled 55 strips brought into register with the machine

and, in general, to provide a simple, efficient, economical and rugged mechanism of the character described.

In the drawings wherein I have shown my invention as applied to a machine for making 60 spring strips for a cushion of the Marshall type,—

Fig. 1 is a plan view of the machine.

Fig. 2 is a section taken on the line 2—2 of 65 Fig. 1.

Fig. 3 is a section taken on the line 3—3 of Fig. 1.

Fig. 4 is an enlarged view of a portion of Fig. 3, but showing certain parts in a different 70 position.

Fig. 5 is an end view of the retaining tongs or clamps showing a strip of springs held therein preparatory to sewing of the open ends of the pockets; and

Fig. 6 is a perspective view of one of the 75 completed strips with the springs therein and the ends of the pockets closed.

Referring to the drawings it will be observed that the main parts of the mechanism are mounted upon a substantially rectangular 80 cast iron frame or bed 10 which, at either end, is supported by suitable legs as at 11. At one end of the main frame 10 and supported thereby, I mount the spring making or coiling mechanism which may be of any desired 85 type. In the present instance I have indicated a spring coiling mechanism comprising the usual wire supply guides 12, feed rolls 13 and 14, bender 15, convolution spacer 16 and severing mechanism 17, it being understood 90 that means are provided for relieving the pressure between the rolls 13 and 14 during the time when the cutting mechanism 17 is severing the completed spring from the end of the continuous wire supply 18. The rolls 95 13 and 14 are mounted upon constantly rotating shafts 19 and 20, the shaft 19 serving as a power supply for the other mechanisms on the machine.

Near the ends of the frame there are 100 mounted a pair of horizontal cross shafts 21 and 22 which carry the conveyor mechanism. Said conveyor mechanism comprises a pair of endless chains 23 and 24 trained around sprockets as at 25 keyed to shaft 21 and 105 sprockets 26 keyed to the shaft 22. On the shaft 21 there is also keyed a ratchet wheel 27 which is actuated intermittently or step by step by a pawl 28 pivoted on the rock lever 29 which is loosely mounted on shaft 21. 110

The rock lever 29 is actuated by a pull rod 30 connected to lever 29 by a pivot 31, said pull rod 30 being normally pulled upwardly by means of a coil tension spring 32 connected 5 between hooks 33 and 34 respectively fixed on the main frame 10 and on the pull rod 30. On the main drive shaft 19 of the spring coiling mechanism there is keyed a sprocket 35 around which is trained a chain 36, which 10 chain drives a sprocket 37 keyed to a shaft 38 mounted to rotate in bearings formed in a pair of upstanding floor brackets 39 and 40. It will be observed that the sprocket 37 is considerably larger than the sprocket 35 so 15 that the shaft 38 will be driven at a reduced speed. To said shaft 38 there is also keyed a pinion 41 which drives a large spur gear 42 keyed to a shaft 43 also mounted to rotate in the brackets 39 and 40. To said shaft 43 there 20 is also keyed a star shaped radial cam 44 formed in the present case with six lobes 45 so as to accommodate strips containing six helicals. In a boss on the side of the floor bracket 39, there is fixed a short stud 46 which 25 furnishes a bearing or pivot for one end of the cam lever 47, said cam lever intermediate its length being equipped with a cam roll 48 cooperating with the cam 44. In the present instance, I have shown cam lever 47 as being 30 bifurcated or in two parts between which the cam roll 48 is rotatably mounted. The outer end of the lever 47 carries a pin 49 by which said lever is pivotally connected to the lower end of the ratchet pull rod 30 so that as the 35 shaft 43 revolves there will be a reciprocation of said pull rod 30 for each lobe of the cam 44, that is to say, six reciprocations for each revolution of the shaft 43.

These springs or helicals as they are coiled 40 and cut off by the spring mechanism, are deposited on supports carried by the chains 23 and spaced in conformity with the spacing of the pockets in the strip, the stroke of the ratchet mechanism which drives said chains being 45 adjusted accordingly. Each of said supports comprises a substantially horizontally extending trough 50, semi-circular in cross section and of sufficient length to hold or contain a helical. Preferably, the forward edges of 50 said troughs 50 are flanged over or flared slightly as shown at 51 so that each spring as it is cut off by the spring making mechanism will seat itself without catching on the edge of the trough. Also, as shown best in 55 Fig. 3, the inner end of the trough is flared down slightly as indicated at 52 and the outer end is bent upwardly slightly as shown at 53. In order still further to guide the springs and insure their proper position in the supports or troughs 50, I prefer to place a stationary stop strip or guide 54 in front of the outer or delivery ends of the troughs 50, said guide 54 being flared upwardly so that the helicals will not catch on the upper edge of 60 said guide 54. Also in order to line up the

rear edges of the said helicals, I may use an other inner guide member 55 which will force back into proper position in its trough, any spring which extends too far inwardly.

The unfilled strip having open ended pockets is placed with its mouth or open end as shown at 56 in Fig. 3 so as to register and receive a set of six springs delivered from the step by step conveyor. In order to effect such register and to enable the springs to be inserted into said pockets, I provide a series of stationary chutes spaced in accordance with the spacing of the troughs 50 on the conveyor and adapted to register therewith. Each of said chutes comprises a small bracket 57 secured to the top 58 of the main frame 10 and serving as a support for a sheet metal cylinder 59 of sufficient internal diameter to admit the helical 60 when thrust therethrough in a direction longitudinally of its axis. In order to enable the open ends of the flexible pockets of the strip to be conveniently applied over the chute sections 59, the latter is preferably equipped with resilient fingers or straps 61 spaced around the periphery of the cylinder 59 and bent so that normally the outer ends of said fingers 61 will come substantially to a point as indicated in Figs. 1 and 3. Said straps or fingers 61 constitute in effect, outer flexible extensions of the cylinders or chute sections 59.

Since it requires some considerable time to remove a filled strip and to apply an unfilled strip to the delivery chutes, I find it advantageous to deliver the entire set or gang 100 of springs simultaneously. This enables the springs to be fed or delivered continuously to the conveyor while the change from a filled to an unfilled strip is being made. To this end I employ a delivery mechanism 105 equipped in the present instance with a series of six pushers or plungers. Each of said pushers or plungers comprises a disc or collar 62 mounted on the ends of push rods 63, each of which slides in a long bearing 64 on a bracket 65 secured to the table 58 of the main frame. The disc or collar 62 is slightly larger than the diameter of the spring 60 but is small enough to enter the chute 59. For a purpose hereinafter to be described, there are cut in the disc 62 a pair of vertically aligned, diametrically opposed notches 66.

Each of the plunger rods 63 is flattened at its rear end as shown at 67 and apertured to fit a bail rod 68 so that actuation of the bail 68 will operate all of the plungers simultaneously. Said bail 68 adjacent its ends, constitutes a bearing for a pair of flanged rollers 69, each of which is straddled or positioned within a slot 70 in the upper end of 120 an actuating lever 71. Each of said actuating levers 71 is keyed to the end of a rock shaft 72, journaled in spaced bearings 73 and 74 of a bracket 75 bolted to frame 11. Said shaft 72 is oscillated by a depending lever 76 keyed 125

thereto and having at its lower end a cam roll 77. The cam roll 77 is located in the slot or groove 78 of a barrel cam 79 keyed to the time shaft 43. Said barrel cam 79 is equipped 5 with a single actuating lobe 80 so that the plungers 63 will be actuated once for each revolution of the time shaft 43. It will be understood that the lobe 80 is so shaped and dimensioned that the plungers 63 are enabled to make substantially a complete reciprocation during a rest interval of the conveyor, that is to say, between a pair of adjacent step by step movements thereof.

It is desirable to have some means for 15 maintaining the springs or helicals within the pockets, and preferably in the partially compressed condition therein until the pocket closing has been effected, that is to say, until the edges of the open ended pockets have been 20 sewed together by a longitudinal line of stitching extending along the edge of the strip as indicated in Fig. 6. Devices for the purpose of retaining the springs in said position in the strip are indicated in some of the 25 patents previously referred to. However, manually controlled or operated devices are usually not economical or efficient for high speed production, nor would it be convenient to use a manually operated device in conjunction 30 with a continuous or automatic high speed machine of the type disclosed herein. Therefore, I prefer a retaining clamp or tongs which is capable of being actuated automatically in synchronism with the inserting 35 mechanism.

The retaining devices are mounted upon a downwardly offset portion 81 of the frame table 58 which serves as a temporary support or guideway for a removable base plate 82 on 40 which the tongs or retainers proper are mounted. Said base plate 82 at its inner end or edge is interlocked with the table 58 by undercutting the offset portion thereof so as to form an overhanging ledge 83 under 45 which the inner edge of the base plate 82 extends. The base plate 82 is prevented from backing off during the insertion operation by an abutment bar 84 extending along the rear edge of the plate 82 and carried by a 50 pair of arms 85, the outer ends of which are curved downwardly as shown in Fig. 3 to rock on pins 86, on stationary lugs 87, on side 88, of frame 11. A handle 89 on one of the 55 hinged arms 85 is provided to facilitate the rocking back of the lock bar 84 into dotted line position as indicated in Fig. 3 whenever it is desired to free the base plate 82 in changing the strip.

The base plate 82 is made with a plurality 60 of upstanding brackets 90, forming bearings for the spaced superposed vertically aligned rock shafts 91 and 92. Said rock shafts 91 and 92 carry six sets of tongs or clamps, each 65 set comprising an upper jaw member 93 keyed to shaft 91 and a lower jaw member

94 keyed to shaft 92. Each of said jaws is made with a short claw 95 shaped and positioned so that when the jaw shaft is suitably rocked on its axis at the time when the inserting plungers are at their outer limit of 70 movement, the claw 95 will enter notch 66 and engage behind the rear coil of the partially compressed helical.

I employ special mechanism for maintaining the jaws of the tongs in open position and 75 also in closed position. Referring to Fig. 5, it will be observed that on the outer ends of the shafts 91 and 92 there are keyed respectively two double ended arms 96 and 97 80 equipped with intermeshing mutilated spur gear portions 98 and 99 so that the shafts 91 and 92 will always move in unison. The outer ends of the arms 96 and 97 have mounted thereon pins 100 and 101 connected together by a coil tension spring 102, said pins 100 and 101 being so positioned that the arrangement comprises in effect a cross-the-center spring mechanism for holding the rock 85 shafts 91 and 92 in either of two positions. 90 A pair of stop pins 103 and 104 limit the opening movement of the tongs through being engaged by the sides of the inner ends of the rock arms 96 and 97. A handle 105 on the outer end of arm 96 enables the tongs to 95 be conveniently released from the pocket strip after the same has had its pockets sewed or closed.

The tongs are automatically actuated by the movement of the plungers 62. For effecting this, I equip said pushers or plungers with an extension stud 106 of suitable length to engage the ends of small trip arms 107 and 108 keyed respectively to the shafts 91 and 92, preferably, being made integral with the 105 jaw members 93 and 94 as shown. It will be readily understood that during the final portion of the movement of the pushers, the extension 106 when it engages trip arms 107 and 108 will cause the shafts 91 and 92 to rock 110 on their axes and when the spring 102 "crosses the center", the clamps or jaws 93 and 94 will snap down into the position shown in Fig. 4.

The described details of construction and 115 operation being illustrative of only one phase of my invention, it will be understood that the scope of same should be determined by reference to the appended claims, said claims being construed as broadly as possible, consistent with the state of the art.

I claim as my invention:

1. In a machine for inserting springs into open ended flexible pockets, the combination of a pusher for thrusting a spring into a 125 pocket, a retainer for holding the spring in said pocket after its insertion, and means for actuating said retainer synchronized with the pusher.

2. In a machine for inserting springs be- 130

tween the folds of a two-ply flexible strip, the combination of a chute adapted to extend between said folds, a plunger reciprocable in said chute to force a spring therethrough and between said folds, a retainer for preventing retraction of said spring, and means for actuating said retainer synchronized with the plunger.

3. In a machine for inserting springs between the folds of a two-ply flexible strip, the combination of a chute adapted to extend between said folds, a plunger reciprocable in said chute to force a spring therethrough and between said folds, a retainer for preventing retraction of said spring, and means for actuating said retainer operated by the movement of the plunger.

4. In a machine for inserting springs between the folds of a two-ply strip, the combination of a chute adapted to enter between said folds, a support movable relative to said chute to bring a spring into register with said chute, a pusher for thrusting said spring through said chute into the space between said folds, and a retaining device for prevent-

ing retraction of said spring synchronized with the pusher.

5. In a machine for inserting springs between the folds of a folded flexible strip, the combination of a conveyor having a plurality of spring receiving members secured thereto, means for advancing said conveyor and receiving members step by step, means for delivering springs one by one to said receiving members as the latter are moved into receiving position, a plurality of spaced chutes having portions adapted to enter between the folds of said strip, said chutes being disposed to one side of the receiving members carried by said conveyor so as to register axially with a corresponding plurality of receiving members when the latter are stationary, a pusher for simultaneously thrusting a plurality of springs from said receiving members through said chutes and into said strip, and means for actuating said pusher when a predetermined number of loaded spring receiving members register with said chutes.

JOHN F. GAIL.
